(57) **CLAIM**

The ornamental design for a hospital garment, as shown and described.

DESCRIPTION

FIG. 1 is a perspective view of the hospital garment showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is an enlarged, fragmentary perspective view thereof, showing only the pants;

FIG. 7 is an enlarged, fragmentary front elevational view thereof, showing the full opening of the pants;

FIG. 8 is an enlarged, fragmentary view thereof, showing only the shirt portion of the garment;

FIG. 9 is an enlarged, fragmentary view thereof, showing the tab member on the lower portion of the pants

FIG. 10 is a rear elevational view thereof, showing a tie closure and tabs, and;

FIG. 11 is a front elevational view thereof, showing a tie closure and tabs.

The broken lines, showing portions of the human form in FIGS. 1-11, form no part of the claimed design.

The broken lines showing tie closures and tabs, in FIGS. 10 and 11, form no part of the claimed design.
